(57) **CLAIM**

The ornamental design for a Universal Serial Bus electrical wiring device, as shown and described.

DESCRIPTION

FIG. 1 is a front view showing the USB electrical wiring device, the device includes two single USB port openings and a receptacle disposed at the opposite end, with broken lines depicting unclaimed subject matter that forms no part of the design.

FIG. 2 is a front view showing the USB electrical wiring device, the device includes two single USB port openings and a receptacle disposed at the opposite end, with broken lines depicting unclaimed subject matter that forms no part of the design.

FIG. 3 is an isometric view of the USB electrical wiring device depicted in FIG. 1, with broken lines depicting unclaimed subject matter that forms no part of the claimed design;

FIG. 4 is an isometric view of the USB electrical wiring device depicted in FIG. 2, with broken lines depicting unclaimed subject matter that forms no part of the claimed design;

FIG. 5 is a side view of the USB electrical wiring device depicted in FIG. 1 and FIG. 2, with broken lines depicting unclaimed subject matter that forms no part of the claimed design;

FIG. 6 is a first end view of the USB electrical wiring device depicted in FIG. 1 and FIG. 2, with broken lines depicting unclaimed subject matter that forms no part of the claimed design; and,

FIG. 7 is a second end view of the USB electrical wiring device depicted in FIG. 1 and FIG. 2, with broken lines depicting unclaimed subject matter that forms no part of the claimed design.
